ATTORNEY

UNITED STATES PATENT OFFICE

LERoy B. TAYLOR, OF CLEVELAND, OHIO

REVERSIBLE WINDOW

Application filed August 8, 1929. Serial No. 384,386.

This invention relates to reversible windows, of the type which allows the sash to swing on horizontal pivots which are attached to the lower part of the sash and are 5 also pivotally hung between side arms which are pivoted at their upper ends to the casing.

Such a window is shown in my Patent No. 1,722,774.

The object of the present invention is to 10 provide improved sash supporting arms which are off-set to clear the flange of the sash, and pivoted to sash at points that will permit both sash to be completely reversed without interfering with each other at meeting rail or at head or sill.

Another object of the invention is to provide an improved spring catch which will hold the sash in an open, closed or partly closed position.

20 Other objects will be evident from the following description and the accompanying drawings, in which:

Fig. 1 is a front elevation and is indicated by lines 1—1 on Fig. 2, and broken 25 away to show the reversed sash in section. Fig. 2 is a sectional view showing the installation and operation of the window. Fig. 3 is a section in plan on line 3—3 of Fig. 1.

30 Referring specifically to the drawings: A window casing consisting of a head 1, jambs 2 and sill 3, is made to fit the opening in the wall of the building. A metal channel 4 is formed or inserted at recess 5 in each jamb 35 2 and extends the full length of the frame between the head 1 and the sill 3, and has countersunk holes 6 at convenient intervals into which the bullet headed spring pivots 7 slip and catch as the sashes 8 and 8^a are 40 opened or closed.

These pivots 7 consist of a bullet head 9 with a shank 10 over which the coil spring 11 fits, the complete unit being housed and fastened by peening the end of shank 10 after 45 it is in the cylindrical holders 12 which are attached to the ends of the sashes 8 and 8^a.

The arms 13 and 13^a for holding the sashes 8 and 8^a are shown in Fig. 2 extended at 50 different angles to show the manner in which sashes 8 and 8^a are reversed. These arms 13

and 13^a are fastened to jambs 2 by screws 14 which allow the said arms to swing freely. The sashes 8 and 8^a are cut away at 15 to allow the arms 13 and 13^a to clear the flange of the aforementioned sashes. The springs 16 and 17, which are corrugated to retard the movement of the sashes 8 and 8^a, are fastened by screws 18 to head 1 and jamb 2.

Fastened to the reverse or lower end of sashes 8 and 8^a are spring strips 19 and 19^a 60 which close the opening 20 at the meeting rails and at sill 3.

Both sashes 8 and 8^a are rabbeted for the arms and are cut away at the top and bottom where the curve of the arms 13 and 13^a 65 protrude.

An ordinary lock catch may be used for holding the sashes closed.

To open the upper sash 8, the upper end of the sash is pulled forwardly which swings 70 sash 8 outwardly as shown by dotted lines in Fig. 2, the spring pivots 7 sliding up in the channels 4, slipping in and out of holes 6 in said channel 4.

The arms 13 swing with the sash 8 on the 75 spring pivots 7, and the corrugated springs 16 and 17 retard the movement of the sash 8 by acting on housing 12 of spring catch or pivots 7, and so prevent slamming. The sash 8 may be swung to a horizontal position 80 or completely reversed if desired.

The lower sash 8^a is operated in the same manner.

Various changes may be made in the details of the structure within the scope of the 85 following claims.

I claim:

1. A reversible window comprising a casing the jambs of which are provided with notches, a reversible swinging sash, pivoted arms connecting the sash and casing, and yielding pivots mounted on the sash and 90 slidable up and down along the jambs and engageable in said notches to hold the sash in desired positions.

2. A reversible window as set forth in claim 1, said pivots comprising pins with rounded heads engageable in the notches, and springs pressing said pins outwardly into the notches.

95

100

3. A reversible window as set forth in claim 1, the sash having cylindrical holders mounted thereon and the pivots comprising pins with rounded heads engageable in the notches, the pins being housed in said holders, and springs coiled around the pins in the holders.
4. A reversible window as set forth in claim 1, the arms being offset at the ends adjacent the casing to clear the sash.
- 10 5. A reversible window as set forth in claim 1, the sash having flanges, and said flanges being cut away to permit the arms to clear the same.
- 15 6. The combination stated in claim 1, the springs between the sash and the casing to retard the movement of the former.

In testimony whereof, I do affix my signature.

LEROY B. TAYLOR.
